US00D836355S

(12) United States Design Patent (10) Patent No.: US D836,355 S
(45) Date of Patent: * Dec. 25, 2018

(54) CHAIRS FOR GYNAECOLOGICAL EXAMINATIONS

(71) Applicant: SCHMITZ U. SÖHNE GMBH & CO KOMMANDITGESELLSCHAFT,
Wickede (Ruhr) (DE)

(72) Inventor: Rainer Schindhelm, Rotthalmünster
(DE)

(73) Assignee: SCHMITZ U. SOEHNE GMBH & CO. KOMMANDITGESELLSCHAFT,
Wickede (Ruhr) (DE)

() Term: 15 Years

(21) Appl. No.: 35/502,853

(22) Filed: Feb. 10, 2017

(80) Hague Agreement Data

Int. Filing Date: Feb. 10, 2017

Int. Reg. No.: DM/095679

Int. Reg. Date: Feb. 10, 2017

Int. Reg. Pub. Date: Apr. 28, 2017

(30) Foreign Application Priority Data

Aug. 12, 2016 (EM) 003 339 142

(57) CLAIM

The ornamental design for a chair for gynaecological examinations, as shown and described.

DESCRIPTION

1.-4. Chairs for gynaecological examinations

1.1 : Perspective

1.2 : Back

1.3 : Right

1.4 : Left

1.5 : Perspective

1.6 : Perspective, with the front element remove in an alternate configuration of use

2.1 : Perspective

2.2 : Back

2.3 : Right

2.4 : Left

2.5 : Perspective

3.1 : Perspective

3.2 : Back

3.3 : Right

3.4 : Left

3.5 : Perspective

3.6 : Perspective, with the front element remove in an alternate configuration of use

4.1 : Perspective

4.2 : Back

4.3 : Right

4.4 : Left

4.5 : Perspective in an alternate configuration of use

1 Claim, 22 Drawing Sheets
